UNITED STATES PATENT OFFICE

2,015,380

STEAM ENGINE VALVE GEAR

Walter W. Dooley, Knoxville, Tenn.

Application July 9, 1934, Serial No. 734,340

1 Claim. (Cl. 121—163)

This invention appertains to new and useful improvements in means for controlling the reciprocating motion of the steam induction and exhaust valve for all types of reciprocating steam engines.

An important object of the present invention is to provide a control for varying the valve lead at the will of the operator by shifting the control point of the conventional lap and lead lever 10 along the axis of the said lever, thereby shortening the distance through which the control point will move horizontally.

Another important object of the present invention is to provide means for varying the cut-off with modifications of the lead by changing the position of the radius rod center with respect to the lap and lead lever through the movement of the actuated end of the radius rod in a developed arc.

Still another important object of the present invention is to provide a link structure whereby the actuated end of the radius rod is driven.

A further object of the invention is to provide a worm and gear drive for the eccentric 25 with means for reversing the motion of the worm to acquire a reversing action of the engine independently of the lap and lead adjusting means.

Other important objects and advantages of the 30 invention will become apparent to the reader of the following specification.

In the drawings:

Figure 1 is a side elevational view partly in section showing the mechanism at one side of 35 a locomotive.

Figure 2 is a fragmentary top plan view of the eccentric drive.

Figure 3 is an enlarged vertical sectional view taken substantially on line 3—3 of Figure 2.

Figure 4 is a side elevational view of the worm shown in Figure 3.

Figure 5 is an end elevational view of the worm shown in Figure 4.

Figure 6 is a side elevational view of the yoke 45 for the worm.

Figure 7 is an end elevational view of the yoke.

Figure 8 is a side elevational view partly in section showing the squared shaft for the worm gear.

Figure 9 is a side elevational view of the oscillatory link.

Figure 10 is a sectional view taken substantially on line 10—10 of Figure 9.

Figure 11 is an edge elevational view of the 55 radius rod.

Referring to the drawings wherein like numerals designate like parts, it can be seen that a description of the gear at one side of the locomotive will suffice as it is to be understood that the construction of each side of the locomotive is identical, with the exception of the worm drive which will be described subsequently.

In the drawings wherein like numerals designate like parts, it can be seen that numeral 5 represents the drive cylinder in which the piston 10 6 is located while numeral 7 represents the slide valve for distributing steam to the cylinder 5. From the piston 6 extends the pitman 8 which connects to the usual main cross head 9. An arm 10 extends from this crosshead 9 and to this is 15 pivotally connected the usual lap and lead lever 11 which is pivotally connected as at 12 to the stem 13 of the distributing valve 7. Numeral 14 represents a crosshead pivotally supporting one end of the radius rod 14' which is provided with 20 a laterally disposed pin 15 operating in the longitudinally and axially disposed slot 16 in the lap and lead lever 11.

An oscillating link 17 is clearly shown in Figures 9 and 10 and consists of a rectangular frame-like 25 bar 18 having longitudinally extending slots 19—19 in the side portions a—a, these slots 19 being on a definite curve predetermined to properly shift the rod 14. It will be observed that the upper portion of this frame 18 is provided with 30 laterally disposed trunnions 20—20 journaled through portions b—b of the locomotive frame 21 and that the radius rod 14' extends rearwardly through the frame or bar 18, that is between the side portions a—a to connect by the pivotal 35 link 22 to the bell crank 23, the latter in turn being controlled by a remotely actuated rod 24. The radius rod 14' at the oscillatory link 17 is provided with laterally disposed trunnions 25 which ride in the slots 19—19. The lower portion of the bar 18 (see Figure 10) is provided with a transversely extending bore 26 to accommodate a pivot pin 27 whereby one end of the pitman 28 is pivotally connected to this link bar while the opposite end is eccentrically and pivotally connected to the eccentric wheel 29. It will be observed that all of these details are duplicated on the other side of the locomotive and that the two eccentric wheels 29 are located on a common shaft 30, which, as shown in Figure 2, is provided 50 with a beveled gear 31 with which meshes the beveled pinion 32. The beveled pinion 32 is carried by a short shaft 33 which is connected to the extension 34 of the squared shaft 35 by a slit or splined connection 36.

The shaft 37 of the drive wheels 38—38 is, as shown in Figure 3, provided with a gear 39 which meshes with the slide worm 40 on the squared shaft 35. The squared shaft 35 is free to rotate in the bearing mount 36, while the worm 40 is free to slide on this shaft and this sliding action can be effected by the rod 41. It is preferable that this rod be actuated by a compressed air cylinder piston and, as is shown, the rod connects to an ear 42 at the top of the U-shaped harness or yoke 43 which is provided with a fork 44 at each end thereof for engaging with a reduced portion 45 at the corresponding end of the worm.

It can now be seen that the valve lead can be adjusted at the will of the operator by actuating the rod 24 and through the link 17 shifting the control point at 15 (see Figure 1) up or down along the axis of the lap and lead lever 11, thereby shortening the distance that the control point will move horizontally.

It will be observed that the worm gear 40 serves to drive the eccentric wheel 29 and consequently the valve 7 in their definite adjusted positions. In order to reverse the motion of the engine independently of the lap and lead adjustment rod 24, the worm gear 40 is simply shifted horizontally while in mesh with the driving gear 39. By this horizontal movement the worm gear is rotated in a direction counter to that of the previous motion, thus revolving the eccentric wheels 29 through an arc proportional to the horizontal movement of the driven worm. Through the connecting link or pitman 28 to the oscillatory link 17 controlling the movement of the reciprocating valve with varying lap and lead, the dis-

tance of the valve travelled in the reverse direction is made proportional to the horizontal distance the driven worm is moved, thus placing the valve in a position for steam admission to the opposite end of the steam engine piston 6 and thereby reversing the motion of the engine in the direction of the driven crank. This change in valve travel can be accomplished for any position of the main engine crank or at any point in the valve or piston stroke, being a simple, positive, efficient and effective means for reversing the engine through a change in the relative positions of the main engine driving crank pins and the connection on the pitman 28 with the eccentric wheels 29.

While the foregoing specification sets forth the invention in specific terms, it is to be understood that numerous changes in the shape, size, and materials may be resorted to without departing from the spirit and scope of the invention as claimed hereinafter.

What is claimed is:

Reversing mechanism for distributing valves of steam engines comprising a drive wheel operative gear, a slidable control rod, a worm having a polygonal opening therethrough, a rotatable shaft having a polygonal cross sectional portion for disposition through said worm along which the worm is slidable, a yoke carried by the control rod and engaged with the worm, said slidable control rod being operative to shift said worm on the shaft, and actuating means responsive to the rotation of the shaft for regulating a distributing valve with which it is connected.
